APPARATUS FOR THE PRODUCTION OF
COMBUSTIBLE GAS FROM SOLID FUEL

Charles Whitfield, Acton, London, England

Application July 7, 1930, Serial No. 465,966
In Great Britain August 3, 1929

8 Claims. (Cl. 126—163)

This invention relates to gas producers where in combustible material is burnt as fuel for the production of gas.

With the present methods and apparatus the loss of efficiency is principally due to the absence of adequate control for the air supply and to the conditions under which the air is brought into contact with the fuel. The function of the grate is to support the fuel bed so that the air may have access to the underside of the same. The air apertures in the grate are therefore more or less subject to be closed or covered by the fuel itself so that they are in the aggregate of sufficient area to admit the air freely up to the maximum demand for the grate through the uncovered portions. The volume of air passing through the grate as a whole, is therefore determined by the total resistance of the fuel bed to the "draw", whether or not such "draw" is assisted by forced or induced air supply to the grate. The volume of air passing through any one part of the fuel bed is therefore dependent upon the total resistance of such part of the fuel bed (i. e. both the resistance in the body of the fuel bed and the resistance at the grate due to partial stoppage of the grate apertures by the fuel), the local resistance of the grate itself being substantially negligible as above explained, and as in practice, considerable variation of fuel bed resistance is bound to exist, unequal distribution of the air takes place from the very start, resulting in unequal combustion. The unequal combustion thus produced tends to accentuate the original difference of resistance in the fuel bed so that the effect is cumulative. Unequal combustion is at present only controlled by the use of a relatively deep or heavy bed of fuel which reduces the proportionate effect of unequal height of combustion in the fuel bed and allows time for the combustion to spread from the higher points of combustion which is assisted by the levelling and settling action of the bed of fuel due to the weight thereof. Unequal combustion means unequal temperatures and while a certain minimum temperature is required the difficulty at present experienced is to maintain such temperature and at the same time prevent the formation of "clinker" away from the grate resulting from the unequal combustion which occurs.

Any attempt to obtain uniform combustion by the reduction of the air supply area at the grate surface, results in "blow-pipe" action of the air on the fuel and the formation of "clinker" away from the grate.

The formation of "clinker" in the fuel mass of

itself renders it necessary to have a much greater depth of fuel in the producer than would be required if the combustion could be effected at the grate and equally over the entire surface, for, in a gas producer it is essential that the CO₂, which is produced when and where the clinker is being formed, must pass through a mass of incandescent carbon in order to be converted into CO. Air passing through "clinker" in the body of a producer, that is to say, away from the grate, results in practice in an increase of the CO₂ content of the gas.

The object of the invention is to overcome or mitigate the disadvantages, as above set out, of the present methods and plant.

According to the invention, the improved method of obtaining uniform combustion of fuel on a grate for the production of gas consists in providing a restrictive sectional control of the air supply away from and preceding the grate surface, such control giving a predetermined resistance to the passage of air so that each section admits only the volume of air required to produce its proportion of carbon monoxide to be obtained from the carbon content of the fuel.

According to further features of the invention, the air apertures of the grate are such as to provide as large an area as possible consistent with supporting the fuel. Other features of the invention are embodied in the description which follows and in the appended claims.

Upon the accompanying drawings:

Fig. 1 is a plan showing the side and central firebars as used in constructing a grate according to one example of the invention.

Fig. 2 is a front end elevation of some of the firebars of the grate.

Fig. 3 is a rear end elevation of Fig. 2.

Fig. 4 is a side elevation of the front end of one of the firebars showing the control shutter.

Fig. 5 is a side elevation of the rear end of one of the outside bars, showing the end shutter.

Fig. 6 shows cross sectional views of the firebars shown in Fig. 1.

Fig. 7 is a cross sectional elevation of one half of the lower part of a gas producer showing a modified construction of grate according to the invention.

Fig. 8 is an enlarged elevation showing the details of assembly of the bar used in Fig. 7.

Fig. 9 is a plan of Fig. 8 with parts shown in section.

Fig. 10 is a cross-sectional view on line 10—10 of Fig. 8.

Fig. 11 is a sectional illustration of the side and

intermediate bars of a further modified construction, showing the bars separated.

As illustrated in Figs. 1 to 6, the fire grate consists of longitudinal firebars of girder section, *a* being the left hand outside bar, *b* one of the centre bars, and *c* the right hand outside bar. The lower flanges *d* of the bars are proportioned so as to meet, forming relatively large, open-ended, longitudinal air chambers. The upper flanges *e* 10 of the bars are thicker and slightly narrower, except at their ends and have notches *f* at relatively close intervals, the notches extending in depth to the web. There are therefore longitudinal air slots between each bar as well as the radiating slots therefrom provided by the notches, the width of the slots being proportioned according to requirements of the grates, in particular as to the fuel to be used. The bars are provided with an intermediate wider part *f*¹ on each side between 15 the notches, so as to provide spacing members for the bars intermediate of their length. The grate may be suitably arranged in a general horizontal plane although it may be inclined. For completing and controlling the supply of air to the longitudinal chambers provided between adjacent 20 grate bars or girders and also to enable clearing the chambers, shutter flaps are pivoted between the girders, both at the front and at the back of the grate. Both shutters being mounted for 25 swinging in the same direction, a clearing rake may be used to push out whatever may have collected, if and when necessary. The front flaps *g* are between the bars and short so as to leave an opening below them, while the back flaps *h* are 30 arranged over the ends of the bars so as entirely to close the end of the air chambers between the bars. The front flaps *g* are pivoted on lugs *j*' cast on the inside of the bars, while the rear flaps *h* are 35 pivoted on a rod supported by brackets *h*¹ secured to the end bars.

As shown in Fig. 6, *a* is the left hand side fire bar, *b* is one of the central or intermediate fire bars and *c* is the right hand side fire bar. Likewise, in the form of grate construction illustrated in Figs. 7, 8, 9 and 10, there are employed 40 fire bars suitably shaped and arranged so as to provide a left hand side fire bar, central or intermediate fire bars and a right hand side fire bar. In the form of gas producer grate shown in Figs. 45 7, 8, 9 and 10 there is a subdivision of the longitudinal chambers—which longitudinal chambers are provided between the bars—and separate admission of air to each sub-chamber is provided. This subdividing of the longitudinal chambers 50 into sub-chambers so as to form the sub-chambers is effected by providing a central bar *k* in and for each longitudinal chamber on which bar are secured angle pieces *m* arranged in pairs at uniform intervals along the bar and together 55 forming dividing members extending across the longitudinal chamber. The firebars are provided with vertical ribs *b*² on their sides, spaced at similar intervals, with which the dividing members *m* will normally register. The central 60 bar *k* is mounted to be slidable longitudinally within the chamber so that the dividing members *m* may act as clearers to remove any ash which may have fallen through into the chambers. The underside or bottom of the chambers 65 is formed or defined by longitudinal plates *n*, secured by screws *n*¹ to the grate bars and having longitudinal slots or notches *o*, arranged centrally of the chambers and spaced at the same 70 intervals as the vertical ribs and divisions so as 75 to be between the same and each provide the air

supply for the subdivision of the longitudinal chamber in which it lies. The slots or notches *o*, though wider than the grate apertures, are short and of a less area than the grate apertures for the subdivision, so that while providing effective control or restricted air supply according to the invention, they are large enough to release any ash or bits of fuel which may fall into the chamber.

In the further example as shown in Fig. 11, there is employed the left hand side fire bar, central or intermediate fire bars, and the right hand side fire bar, respectively designated *p*, *q* and *r*. Said fire bars are formed with flanges *p*¹, *q*¹ and *r*¹, respectively which are notched at *s*. The notched flanges take the place of the plates *n* in the preceding example. Longitudinal bars *t* carrying angle pieces *u* are provided, similar to the bars *k* and angle pieces *m*, and the firebars are formed with vertical ribs *v* similar to the ribs *b*².

The slots and spaces at the grate surface are such as to provide as large an air supply area as possible consistent with practical requirements as to strength and durability. Those in the grate illustrated herewith are suitable in size for most 100 of the usual fuels but the same area may be obtained with a greater number of narrower slots and spaces to provide a surface for use with fine or crushed fuel.

Experimentally, a suitable inlet area was found 105 to be about one sixth or less of the total area of the apertures of the grate section associated therewith, or about one eighteenth of the area of the said grate section surface. Useful control may, however, be obtained even with an inlet 110 area for each chamber which is as much as one-eighth of the area of the said grate section surface. For efficient working a grate section of not larger than half a square foot is preferred and not less than four sections are desirable in the 115 grate.

In use, the restriction or control of the air supply is obtained at the entry to the air chambers instead of at the grate surface, so that a low velocity, steady and uniformly limited and 120 distributed supply of air passes up through the air spaces of the grate and renders it possible to produce gas containing a smaller percentage of CO₂ on a thin bed of fuel than is possible on a deep bed to which this method of control has not 125 been applied. It therefore follows, also, that a producer having this grate will be more efficient since the resistance to the flow of gas will be more 130 uniform, a lower temperature in the gas will reduce the loss of sensible heat and also the wear 135 and tear incidental to higher temperatures, combustion being effected under conditions of lower air velocity results in temperatures sufficiently high to effect the complete gasification of the 140 fixed carbon, yet low enough to prevent the dissociation of the methane and other fixed hydrocarbons. The improved grate, as a gas producer, 145 is capable of burning small fuel, or refuse, and of providing a high quality of gas therefrom.

It will be obvious that variations in constructional details may be made without departing from the invention, the essential feature of which is the provision of a grate wherein the air supply is controlled in such manner as to allow of uniform distribution, that is, all parts of the grate 145 area are under control, individually and (or) collectively, and capable of uniformity of action.

What I claim is:—

1. A grate for the combustion of fuel for the production of a combustible gas comprising bars 150

- arranged side by side and having upper and lower flanges extending laterally from the sides of the bars so as to form separate closed air spaces between them, means providing vertical partitions between the fire bars subdividing said spaces into chambers along the length of the bars notches in the edges of said upper flanges forming air outlet apertures leading from said chambers, and notches in said lower flanges which collectively provide an air admission aperture for each chamber, the total area of the apertures in the lower flanges being not more than one-third of the total area of the apertures in the upper flanges. 5 80
2. A grate for the combustion of fuel for the production of combustible gas comprising bars arranged side by side and having upper and lower flanges extending laterally from the sides of the bars so as to form separate closed air spaces between them, means providing vertical partitions between the fire bars subdividing said spaces into chambers along the length of the bars, notches in the edges of said upper flanges providing outlet apertures leading from said chambers, notches in said lower flanges which collectively provide an air admission aperture for each chamber, the total area of the apertures in the lower flanges being not more than one-third of the total area of the apertures in the upper flanges, and the ratio of air inlet area to the area of the grate surface apertures being uniform for the whole of the grate area. 15 85
3. A grate for the combustion of fuel for the production of a combustible gas comprising bars arranged side by side and having upper and lower flanges extending laterally from the sides of the bars so as to form separate closed air spaces between them, slideable bars between the fire bars, vertical partitions on said slideable bars for subdividing the chambers along the length of the bar notches in the edges of said upper flanges forming air outlet apertures from said chambers, notches in said lower flanges which collectively provide an air admission aperture for each chamber, the total area of the apertures in the lower flanges being not more than one-third of the total area of the apertures in the upper flanges. 20 90
4. A grate for a gas producer comprising longitudinally extending grate bars each having a vertically extending web section and upper and lower flanges that extend laterally from the web section, the adjacent grate bars being constructed so that there is provided between them and between the upper and lower flanges thereof air spaces that provide separate air supply chambers, the upper flanges of the grate bars being notched to form the grate surface apertures through which air passes from the air supply chamber to the fuel, and means for subdividing the space between adjacent bars into several relatively small air supply chambers, means in the lower wall portion of each chamber for the admission of air to said chambers but only in a restricted manner, the construction of said last named means being such that the air inlet area for any one chamber is not larger than one-third of the grate surface apertures leading from said chamber. 25 95
5. A grate for a gas producer comprising grate bars constructed according to claim 4, being further characterized in that the upper flanges of the bars at the edges of the notched portions are of such a width that at least some of those portions of the adjacent flanges are spaced apart and that the space between those portions of these adjacent flanges form part of said grate surface apertures. 30 100
6. A grate for the combustion of fuels for the production of a combustible gas, said grate comprising bars arranged side by side and having upper and lower flanges extending laterally from the sides of the bars so as to form with the associated parts of the grate separate closed air chambers between the bars, the upper flanges of said bars being constructed and arranged so that they collectively form an apertured grate fuel supporting surface through the apertures of which air from the air chambers can flow to the fuel in the grate, the grate construction also being such that in a wall portion of each chamber other than that part provided by an upper flange there is provided an inlet aperture leading to an air chamber to which the particular aperture corresponds, the inlet aperture for each chamber being not more than one-third of the 35 105
- grate surface apertures leading from the corresponding chamber, and vertical partitions between the fire bars, which vertical partitions carry members whereby each chamber in which the partition is located is subdivided. 40 110
7. A grate for a gas producer comprising a fuel-supporting member formed interiorly with a plurality of separate chambers, said member having air outlet apertures in its upper face extending from each of said chambers and having air inlet apertures in its lower face extending from each of said chambers, the total area of the said air inlet apertures for each chamber being not more than one-third of the total area of the said outlet apertures for the same chamber. 45 115
8. A grate for the combustion of fuel for the product of a combustible gas comprising bars arranged side by side and having upper and lower flanges extending laterally from the sides of the bars so as to form separate closed air spaces between them, slideable bars between the fire bars, vertical partitions on said slideable bars for subdividing the air spaces along the length of the bars into chambers, notches in the edges of the upper flanges forming air outlet apertures from said chambers, notches in said lower flanges which collectively provide an air admission aperture for each closed air space, the total area of the apertures in the lower flanges being not more than one-third of the total area of the apertures in the upper flanges, and said grate being divided in not less than four sections and none of the sections into which the grate is divided being larger than a half square foot. 50 120
- 55 125
- 60 130
- 65 135
